UNITED STATES PATENT OFFICE.

FRIEDRICH ZIEGENFUSS, OF ESSEN-ON-THE-RUHR, GERMANY, ASSIGNOR TO FRIED. KRUPP AKTIENGESELLSCHAFT, OF ESSEN-ON-THE-RUHR, GERMANY.

LUMINOUS PROJECTILE.

1,108,654.

Specification of Letters Patent. Patented Aug. 25, 1914.

Application filed December 26, 1912. Serial No. 738,761.

To all whom it may concern:

Be it known that I, FRIEDRICH ZIEGENFUSS, residing at Essen-on-the-Ruhr, Germany, a subject of the Emperor of Germany, have invented a certain new and useful Improvement in Luminous Projectiles, of which the following is a specification.

This invention relates to luminous projectiles and has for its purpose to increase 10 the strength and duration of the illuminating effect of these projectiles.

In the accompanying drawing, one embodiment of the invention is illustrated, and in said drawing Figure 1 is an axial longitudinal section of a luminous projectile; Fig. 2 is a section on the line 2-2 of Fig. 1; and Fig. 3 shows on a small scale a view of an illuminating body with a descending parachute.

20 The illuminating projectile, as is known of illuminating projectiles that receive a large number of lighting bodies, has a construction similar to a base chamber shrapnel.

25 A designates the shell of the projectile, B the base chamber charge, C the driving disk and D the time fuse, which with the aid of a front end bushing E is connected with the projectile shell. From the time fuse D, two 30 fire tubes F, which are located in grooves a¹ (Fig. 2) of the projectile shell, lead to the base chamber charge B. The fire tubes f stand in communication with the igniting charge d² of the time fuse, through the 35 medium of bores d³ of the time fuse and openings e³ which are provided in a disk e¹, of the front end bushing E.

The projectile space receives two illuminating bodies, each of which is provided, in 40 a known manner, with a parachute L. Each lighting body possesses a lighting mass G, which is located in a pot-shaped container H of the interior diameter of the projectile and is retained in the container H by a 45 cover plate K carrying a bolt J. In the cover plates K, openings k¹ are provided, which terminate at a ring g¹ of pressed powder suitable for igniting the illuminating mass and embedded in the illuminating mass G. Bolts J are screwed into the bottoms of 50 the respective containers and are formed, outside of the container, into a turning stud i¹ for a swivel h¹, to which the parachute L is secured. Furthermore, two studs h² are 55 arranged on each container H which engage in grooves a² (Fig. 2) of the projectile shell

and prevent turning of the illuminating body in the projectile shell.

The container H for the illuminating mass of the lower illuminating body rests through 60 its open side immediately upon the driving disk C. This is provided with recesses for the cover plate K as well as its fastening means, and, beneath the openings k¹ with igniting openings c¹, so that the fire of the 65 charge B can immediately reach the powder ring g¹ of the lower illuminating body. The container H of the upper illuminating body supports itself with its base upon two telescoped bushings M and N, which rest upon 70 the bottom of the container H of the lower illuminating body. Upon its open side, the container H lies against the disk e¹ of the front end bushing E.

In the disk e¹ as well as in the inclosing 75 cover d¹ for the igniting charge d² of the time fuse, openings e² are provided, through which the flame of the igniting charge d² can reach the powder ring g¹ of the upper lighting body.

The bushings M and N receive the parachutes L of the two lighting bodies. Each bushing comprises two half cylinders (Fig. 2), so that after ejection of the illuminating body, they will be separated under the influence of centrifugal force and release the 80 parachute. Between the two parachutes, a disk P is arranged, which can be suitably produced from paper or the like. The inner bushing N is desirable in order to facilitate the insertion of the parachute of the 85 upper lighting body.

The insertion of the illuminating body within the projectile occurs in the following manner: First, the filled container H of 90 an illuminating body is inserted in the projectile shell in such a manner that it rests with its open side upon the driving disk C, whereupon the outer bushing M is set up upon the bottom of the container H and the 95 parachute is pressed into the hollow of this bushing. The parachute will then fill approximately the whole of the bushing M. The disk P is now laid upon the parachute within the bushing M, the inner bushing N is placed upon the rim of the disk P, and the parachute of the second illuminating body is placed in the bushing N. Then the 100 container H of the second illuminating body is placed upon the rim of the bushing N and then with the aid of a press, the bushing N together with the illuminating body 105 is placed upon the rim of the bushing N and then with the aid of a press, the bushing N together with the illuminating body 110

resting upon it is pressed into the projectile until the container H of the upper illuminating body rests upon the bushing M. In accomplishing this, the rim of the disk P will be crimped downward by the bushing N, and the bushing N comes to rest upon the bottom of the under container H. The parachutes are in this manner extraordinarily firmly pressed together, so that the metallic parts (wires) of the parachutes, when under the influence of the force of inertia set up upon hitting the projectile, cannot move and, therefore, cannot produce any destruction of the material of the parachutes.

The operation of the projectile is as follows: The fire of the igniting charge d^2 of the time fuse ignites, immediately, the illuminating mass of the upper illuminating body and, through the medium of the fire tubes F, the base chamber charge B. The latter brings the illuminating mass of the under illuminating body to ignition. After the ignition of the base chamber charge, both illuminating bodies will be ejected through the medium of the driving disk C. By this step, the front end bushing E, with the fuse D, separates from the projectile shell. As soon as the illuminating bodies have left the projectile shell, the bushings M and N are scattered by centrifugal force. The resistance of the air then acts upon the parachutes L and untolds them. The illuminating bodies, while their illuminating masses burn, fall slowly to the earth. After the expulsion of the lighting bodies from the projectile, said bodies together with their parachutes partake of the rotation of the projectile. The speed of the revolution of the illuminating bodies diminishes more slowly than that of the (lighter) parachutes, so that a relative turning between the illuminating bodies and the parachutes takes place. This rotation is permitted by the rotary connection between the lighting body and the parachute, afforded by the swivel h^1 and the stud i^1 , without twisting the cords connecting the parachutes with the illuminating bodies; the unfolding of the parachutes will thus be insured by their rotatable connections with the illuminating bodies.

By the arrangement of the illuminating bodies in such a manner that the illuminating mass of the one illuminating body stands in communication with the igniting charge of the time fuse and the illuminating mass of the other illuminating body stands in communication with the base chamber charge, a more certain ignition of the illuminating masses is obtained. Furthermore, by having the illuminating bodies use the same dimensions as the internal diameter of the projectile as well as by using the described bushings for releasing the parachutes instead of space consuming springs, there is

attained the advantage of keeping the dimensions of the illuminating mass and the parachutes very large. The illuminating bodies thus possess a strong illuminating effect with great burning and falling duration. 70

I claim:

1. An illuminating projectile comprising a projectile shell, a base-chamber charge, and an illuminating body having a parachute contained within and adapted to be expelled from the shell during the flight of the projectile; the diameter of said illuminating body being equal to the internal diameter of the projectile shell. 80

2. An illuminating projectile comprising a projectile shell, having a base-chamber charge; and two superposed illuminating bodies, each having a parachute and located within the shell and adapted to be expelled therefrom, as a whole, during the flight of the projectile; the diameter of each illuminating body corresponding to the internal diameter of the projectile shell. 85

3. In an illuminating projectile, a projectile shell having a base-chamber charge and a front-end igniting charge, and two illuminating bodies superposed in said shell, each having an illuminating mass; said illuminating bodies being introduced, one with its illuminating mass in igniting relation to the igniting charge and the other with its illuminating mass in igniting relation to the base-chamber charge. 95

4. In an illuminating projectile having a shell with a base-chamber charge and a front-end igniting charge; two illuminating bodies superposed in the projectile shell and adapted to be expelled therefrom by said base-chamber charge during the flight of the projectile; each of said illuminating bodies being provided with an illuminating substance and with a parachute, and being introduced with their illuminating masses presented toward and in igniting relation to the respective charges in the shell and with their parachutes confined between the said illuminating bodies. 100

5. In an illuminating projectile having a shell with a base-chamber charge and a front-end igniting charge; two illuminating bodies superposed in the projectile shell and adapted to be expelled therefrom by said base-chamber charge during the flight of the projectile; each of said illuminating bodies being provided with an illuminating substance and with a parachute, and being introduced with their illuminating masses presented toward and in igniting relation to the respective charges in the shell and with their parachutes confined between the said illuminating bodies, there being a separating disk in said shell between said parachutes. 115

6. In an illuminating projectile having a 120

- shell with a base-chamber charge and a front-end igniting charge; two illuminating bodies superposed in the projectile shell and adapted to be expelled therefrom by said base-chamber charge during the flight of the projectile; each of said illuminating bodies being provided with an illuminating substance and with a parachute, and being introduced with their illuminating masses 5 presented toward and in igniting relation to the respective charges in the shell and with their parachutes confined between the said illuminating bodies; said shell having a bushing surrounding said parachutes and 10 abutting both illuminating bodies, whereby the latter are both driven from the shell without injury to the parachutes.
7. In an illuminating projectile having a shell with a base-chamber charge and a front-end igniting charge; two illuminating bodies superposed in the projectile shell and adapted to be expelled therefrom by said base-chamber charge during the flight of the projectile; each of said illuminating bodies 15 being provided with an illuminating substance and with a parachute, and being introduced with their illuminating masses presented toward and in igniting relation to the respecting charges in the shell and with their parachutes confined between the said illuminating bodies; said shell having bushings surrounding said parachutes, adapted to abut against the respective illuminating bodies and to telescope one within the other, in assembling the parts, each of said telescoping bushings being divided longitudinally into parts readily separable to release the parachute when expelled from the shell.
10. In an illuminating projectile having a base-chamber charge and a propelling disk adapted to be driven forward by said charge 20 during the flight of the projectile; an illuminating body comprising a container resting upon the propelling disk and carrying an illuminating mass and having a parachute packed in the shell beyond the said container; the propelling disk and the bottom of said container being perforated to permit ignition of the illuminating mass from the base-chamber charge.
11. In an illuminating projectile having a shell with a base-chamber charge, a propelling disk thereover, a time fuse-head and a frangible bushing coupling the fuse-head to the shell; a pair of illuminating bodies with parachutes in said shell; said illuminating bodies comprising containers fitting the internal diameter of the shell and carrying illuminating masses, said containers being abutted respectively against the base charge propelling disk, and the fuse-head, 25 with their parachutes confined between them, and said shell containing a bushing surrounding the parachutes and abutting against the respective containers and transmitting the expelling thrust from one illuminating body to the other without injury to the parachutes.
12. In an illuminating projectile having a shell with a base chamber charge, an illuminating body with parachute confined within said shell, coaxially with its axis, and adapted to be expelled during the flight of the projectile; said parachute having its cords for uniting it with the illuminating body, connected to the latter by a swivel lying in 30 the axis of the projectile.
- The foregoing specification signed at Bar-
men, Germany, this 5th day of December, 1912.
